US00D481715S

(12) **United States Design Patent** (10) Patent No.: **US D481,715 S**
Sinclair (45) Date of Patent: ** Nov. 4, 2003

(54) **KEY BUTTON ARRANGEMENT FOR A HANDSET**

(75) Inventor: **Matthew Sinclair**, Helsinki (FI)

(73) Assignee: **Nokia Corporation**, Espoo (FI)

(**) Term: **14 Years**

(21) Appl. No.: **29/164,648**

(22) Filed: **Jul. 30, 2002**

(30) **Foreign Application Priority Data**

Jan. 30, 2002 (DK) ..... DA 2002 00081

(51) LOC (7) Cl. **14-03**

(52) U.S. Cl. **D14/247**

Primary Examiner—Jeffrey Asch

(74) Attorney, Agent, or Firm—Banner & Witcoff, Ltd.

(57) **CLAIM**

The ornamental design for a key button arrangement for a handset, as shown and described.

DESCRIPTION

FIG. 1 is a front view of a key button arrangement for a handset showing my new design; and,

FIG. 2 is a perspective front view thereof.

The broken line showing of an exterior boundary structure is for illustrative purposes only and forms no part of the claimed design.
